C. SMITH

CHARGE HEATING DEVICE FOR INTERNAL COMBUSTION ENGINES

Filed Nov. 18, 1922

Fig. I

UNITED STATES PATENT OFFICE.

CHARLES SMITH, OF ST. LOUIS, MISSOURI.

CHARGE-HEATING DEVICE FOR INTERNAL-COMBUSTION ENGINES.

Application filed November 18, 1922. Serial No. 601,775.

To all whom it may concern:

Be it known that I, CHARLES SMITH, a citizen of the United States, a resident of the city of St. Louis, State of Missouri, have invented certain new and useful Improvements in Charge-Heating Devices for Internal-Combustion Engines, of which the following is a full, clear, and exact description, reference being had to the accompanying drawings, forming a part of this specification.

This invention relates generally to improvements in charge heating devices for internal combustion engines, and particularly to a simple and inexpensive device which is adapted to be associated with the intake conductor of an internal combustion engine whereby the explosive charge passing through said intake conductor may be thoroughly vaporized, regardless of atmospheric conditions or temperatures.

It is a well known fact that much difficulty is sometimes experienced, particularly in cold weather, in starting an internal combustion engine due to the fact that the explosive charge comes to the cylinders of the engine in the form of a wet, poorly carbureted mixture instead of a dry vapor which burns with full efficiency when it is ignited by the sparks in said cylinders. The device disclosed in the present application comprises an electrically energized heater which is adapted to be introduced into the intake conductor of an internal combustion engine so that the explosive charge passing through said intake conductor may be thoroughly vaporized and the engine started with ease and facility.

Another object is to produce a heating device of the class described, the heat-generating element of which will not be consumed when subjected to long use.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claim hereunto appended.

Fig. I is a fragmentary side elevation of the carburetor and the intake conductor of

an internal combustion engine, my heating device being associated with said intake conductor.

Fig. II is an enlarged section through my heating device, a portion of the intake conductor being illustrated. 60

Fig. III is a section on line III—III of Fig. II.

Fig. IV is a section on line IV—IV of Fig. II. 65

In the drawings, A designates a carburetor which may be of any suitable construction and has communication with the cylinders of the internal combustion engine (not shown) by way of an intake conductor B. 70

My improved heater is indicated by the reference character H and is partially introduced into the intake conductor B, a threaded opening C being formed through a wall of said intake conductor to receive 75 said heater. In the present embodiment of my invention the heater comprises a body portion 1 in the form of a shell, said body portion being provided with an externally threaded portion 2, an annular flange portion 3 and a heating portion 4. The heating portion 4 of said body portion 1 is adapted to be introduced into the intake conductor B, the threads on the portion 2 engaging the threads within the opening C (Fig. II). 85

The flange portion 3 of the body portion 1 is provided with an internally threaded central opening 5 which receives a threaded plug 6 provided with a central longitudinal opening 7, said opening 7 being provided 90 with an enlarged portion 7' at one end of the plug 6 for a purpose to be hereinafter described. Extended through the opening 7 within the plug 6 is a conductor 8 provided with an enlarged head 9 at one of its 95 ends, said head resembling the heads found on ordinary round headed screws and being provided with a knurled portion 9'. The conductor 8 is spaced apart from the wall of the opening 7, there being a tube of insulating material 10, preferably asbestos, surrounding said conductor. Located in the enlarged portion 7' of the opening 7 and surrounding a portion of the conductor 8 is an 100 insulating member 11, said member being preferably formed of mica and being provided with an annular flange 11' which contacts with the outside face of the plug 6.

The outer end portion of the conductor 8 is 105 threaded as indicated by the reference 110

character 8', said threaded portion being adapted to receive a nut 12. 13 indicates a washer which is interposed between the outer face of the insulating member 11 and the nut 12. Interposed between the nut 12 and the washer 13 is the end of a wire whereby electric energy is conducted to the conductor 8. To insulate the head 9 of the conductor 8 from the plug 6, I employ a washer 14 which may be formed of any suitable insulating material, said washer being located in a recess formed in the inner face of said plug 6 and being interposed between said plug and said head (Fig. II).

15 Located within the heating portion 4 of the body portion of my device is a resistance element 15, said resistance element preferably being in the form of a coiled electric wire whereby heat may be generated. To 20 insure positive contact between the conductor 8 and the resistance element 15, I provide the head of said conductor with an opening 16 into which an end of said heating element is forced. The opposite end of 25 the resistance element bears firmly against the closed inner end of the body portion 1. Interposed between the resistance element 15 and the inside face of the annular wall of the body portion 1 is an insulating member 17 in tube form, said insulating member preferably being formed of asbestos or similar material which, in addition to acting as an insulator, will pack the joints between the plug 6 and the flange portion 3 30 and between the plug 6 and washer 14, thus preventing the ingress of air to the interior of the housing.

In use, my improved heater is screwed 40 into the intake conductor B at a point immediately above the carburetor as shown in Fig. I. When it is desired to start the engine an electric current is supplied to the resistance element 15, thereby causing the heating portion 4 of the body portion 1 to 45 become hot, whereby heat will be radiated from said portion 4. The engine may now be started and the incoming gases from the carburetor upon passing the heated zone within the intake conductor will be

thoroughly vaporized thereby delivering a 50 rich mixture to the engine cylinders.

The head 9 of the conductor 8 is provided with a knurled portion 9' and is also provided with a slot 17', said slot being adapted to receive the end of a screw driver so that 55 said conductor may be held stationary when the nut 12 is applied to the threaded portion of said conductor in assembling the parts associated with the plug 6. The knurled portion is intended to permit said 60 head to be gripped with the fingers, if it should be desired to hold the conductor in this manner.

The resistance element of my improved heating device is contained within a comparatively air-tight compartment, consequently, as there is no means of ingress for the air constituents necessary to support combustion, the danger of said resistance element being consumed by fire resulting from 70 long use is eliminated.

I claim:

A charge heating device for an internal combustion engine comprising a body portion, a portion of which is adapted to be introduced 75 into the intake conductor of said internal combustion engine, an electrically energized, heat-generating element within said portion of said body portion, packing means whereby air is prevented from being drawn into 80 contact with said heat generating element, a plug at the opposite end of said body portion, said plug being provided with a central longitudinal opening, a conductor arranged in said longitudinal opening, said conductor being provided with a head at one end 85 having an opening adapted to receive an end of said heat-generating element and a threaded portion at its other end, a nut on said threaded portion, and insulating members within said longitudinal opening and adjacent to the ends of said conductor whereby said conductor is insulated from said plug.

In testimony that I claim the foregoing I 90 hereunto affix my signature.

CHARLES SMITH.
